Dec. 1250

Leonard M. Volk of Chicago, Illinois,
Letters Patent No. 1250, dated June 12, 1860,

The schedule referred to in these Letters Patent and making part of the same.

To all whom it may concern;

Be it known that I, Leonard M. Volk, of the City of Chicago, in the County of Cook, and State of Illinois, have made or produced a

Dec. 1250

new and original design in round-relief of a bust representing Hon. Abraham Lincoln of Illinois, and I do hereby declare that the following is a full and exact description of the same -

A "Hermes" bust, viz: Head, Shoulders, and breast, cut off above the pectoral muscles, and without drapery or covering of any kind; the head slightly elevated and turned to the right, and what I claim as my production and desire to secure by letters patent, is -

The design for a bust as above described, and represented in the accompanying print -
